DESIGN FOR A SURGICAL TABLE

Eugene E. La Vigne, St. Louis, Mo., assignor to
A. S. Aloe Company, St. Louis, Mo., a corpora-
tion of Missouri

Application August 12, 1937, Serial No. 71,049

Term of patent 7 years

To all whom it may concern:

Be it known that I, Eugene E. La Vigne, a citizen of the United States, residing at the city of St. Louis, State of Missouri, have invented a new, original, and ornamental Design for a Surgical Table, of which the following is a specification, reference being made to the accompanying drawing, forming a part thereof, in which Figure 1 is a perspective view, and Figures 2 and 3

are, respectively, side and end elevational views of a surgical table embodying my new design, Figures 2 and 3 illustrating the respective side and end of the table opposite to the side and end illustrated in Figure 1.

I claim—

The ornamental design for a surgical table, substantially as shown.

EUGENE E. LA VIGNE.
